UNITED STATES PATENT OFFICE.

HENRY ROSE COOL, OF URBANA, OHIO.

DESIGN FOR A TELEPHONE-RECEIVER CAP.

SPECIFICATION forming part of Design No. 31,187, dated July 11, 1899.

Application filed June 13, 1899. Serial No. 720,408. Term of patent 7 years.

To all whom it may concern:

Be it known that I, HENRY ROSE COOL, a citizen of the United States, residing at Urbana, in the county of Champaign and State of Ohio, have invented and produced a new and original Design for a Telephone-Receiver Cap, of which the following is a specification, reference being had to the accompanying drawing, forming a part of this specification, in which is represented a side elevation of the telephone-receiver cap embodying the features of my design.

The leading feature of the design consists of the arrangement of the earpiece C relative

to the band A and body B, the earpiece being 15 at one side and perpendicular to the band A.

The minor features of the design consist in the curvature of the body B to meet the earpiece C and the band A, together with the ogee facing D for the band. 20

I claim—

The design for the telephone-receiver cap herein shown and described.

HENRY ROSE COOL.
